APPARATUS FOR COVERING SHOE HEELS

Donald Lipp, 192-10A 69th Ave., Apt. 1C,
Fresh Meadows, N.Y.

Filed Nov. 3, 1958, Ser. No. 771,267

15 Claims. (Cl. 12—49.1)

This invention relates generally to a novel apparatus for use in the manufacture of shoes, and is especially concerned with the severing of a heel covering sheet in an intermediate stage of heel manufacture. As will become more apparent hereinafter, two separate areas of cutting are involved, one along the breast area of the heel, the other in the top lift area.

As is well known to those versed in the art, the body or core of a heel is smoothly covered by a flexible sheet adhesively secured along the back and sides of the body and extends forward therefrom beyond the front side or breast of the heel body. The forwardly extending cover portions are severed and secured in facing engagement with the breast of the heel body, preferably smoothly thereon, and a separate covering secured on the breast of the heel overlying the severed edge portions. Advantageously, the forwardly extending cover portions are severed to form serrations so as to lie smoothly on the concave surface of the heel breast without crimping or doubling or creating wrinkles on the sides of the heel. Also the forwardly extending cover portions in the top lift area are also advantageously cut for more accurate and proper engagement with the top lift area.

These procedures have heretofore been accomplished by hand, requiring considerable time and effort even by a highly skilled operator, and not infrequently resulting in imperfect work, usually evidenced by an uneven or unsmooth heel breast, wrinkles on the sides, overlap in the breast and cuts into the exposed surface along the breast.

It is therefore one object of the present invention to provide a highly improved apparatus for severing the forwardly extending portions of a heel cover which greatly increases productivity, eliminates the need for skilled personnel, and which greatly enhances the quality of the work.

It is a further object of the present invention to provide apparatus of the type described which is extremely simple in construction and operation, entirely reliable, safe and extremely durable over a long useful life, and which can be manufactured and maintained at a reasonable cost.

Other objects of the present invention will become apparent upon reading the following specification and referring to the accompanying drawings, which form a material part of this disclosure.

The invention accordingly consists in the features of construction, combinations of elements, and arrangements of parts and method steps which will be exemplified in the description hereinafter, and of which the scope will be indicated by the appended claims.

In the drawings:

Fig. 1 is a horizontal view showing the apparatus of the instant invention and taken substantially along the line 1—1 of Fig. 2;

Fig. 2 is a front elevational view showing the instant apparatus, partly in section for clarity of understanding;

Fig. 3 is a sectional elevational view taken substan-

2

tially along the line 3—3 of Fig. 1, somewhat enlarged for greater detail;

Fig. 4 is a partial sectional elevational view taken substantially along the line 4—4 of Fig. 1, also somewhat enlarged;

Fig. 5 is a view similar to Fig. 4 but illustrating a later stage in operation of the apparatus;

Fig. 6 is a perspective view showing a heel before being operated upon according to the instant method;

Fig. 7 is a heel subsequent to being operated upon according to the instant method and apparatus;

Fig. 8 is a partial sectional elevational view similar to Fig. 4, but showing a slightly modified embodiment of the present invention;

Fig. 9 is a sectional elevational view similar to Fig. 3, but showing the embodiment of Fig. 8;

Fig. 10 is a fragmentary front elevational view showing, in enlarged detail, an element of the device of Fig. 9; and

Fig. 11 is a perspective view illustrating the method practised by the apparatus of Figs. 9 and 10.

Referring now more particularly to the drawings, and specifically to Figs. 1 and 2 thereof, the instant apparatus includes a laterally extending, generally horizontally disposed bottom plate or base 10 which is adapted to be supported by any suitable means (not shown) at convenient hand height for an operator.

Secured fast on the upper surface of the base 10 and in facing engagement therewith is a bed plate 11, which is located in the laterally medial region of the base 10, and may be forwardly and rearwardly coextensive with the base. Fixed on the upper surface of the bed 11, as by fasteners 12 and 13, respectively, are a pair of forwardly and rearwardly spaced, laterally elongate guide blocks 14 and 15. That is, the front and rear guide blocks or rails 14 and 15 extend in substantial parallelism with each other, respectively along and coextensive with the front and rear edges of the bed 11. As best seen in Fig. 3, the inner sides of the rails 14 and 15, that is the rear side 16 of the front rail 14, as the front side 17 of the rear rail 15, are undercut and combine with the intermediate upper surface of the bed 11 to define a dovetail-like laterally extending guideway channel or slot.

A front mounting block 20 is fixed on the upper side of the front rail 14 medially thereof, as by fasteners 21, and extends rearward slightly beyond the front rail spacedly over the bed 11, as at 24. A rear mounting block 22 is fixed on the upper surface of the rear rail 15 medially thereof, by fasteners 23 in substantial forward and rearward alignment with the mounting block 20, and extends slightly forward beyond the rear rail spacedly over the bed 11 at 19. The rear mounting block 22 is of substantially greater vertical dimension or height than the front mounting block 20.

Extending forwardly and rearwardly and bridging the space between the portions 24 and 19 of the mounting blocks 20 and 22 is a breast rest or heel contoured supporting plate 25. As best seen in Fig. 3, the supporting plate 25 is of arcuate configuration, being bent to present a convex surface 26 forwardly and upwardly, and a concave surface 27 downwardly and rearwardly. Viewed otherwise, the rearward end region 28 of the supporting plate 25 is secured fast in facing engagement with the upper surface of the rear mounting block 22 by a fastener 29, and extends generally horizontally forward to a medial region 30 which curves downward and forward and terminates in a generally vertically disposed forward end portion 31 secured in facing engagement with the rear surface of the front mounting block 20, as by a fastener 32.

In Fig. 1 it may be seen that the lateral dimension

of the supporting plate 25, between the side edges 35, gradually increases in the forward direction. Thus, the upper surface 26 of the supporting plate 25 is contoured and configured for conforming surface engagement with the breast surface of a desired size and style heel, with the side edges 35 substantially flush with the sides of the heel body. Such conformance need not necessarily be perfect, and for proper operation there even can be variance in size and style. As a matter of fact, the side edges 35 can even preferably be narrower than the sides of the heel body. The undersurface 27 of the supporting plate 25 is serrated or grooved, as at 36 in the curved region 30, by grooves extending laterally of the supporting plate and opening through opposite side edges 35.

Slidable in the channel or guideway defined by the bed 11 and rails 14 and 15, on opposite sides of the supporting plate 25, are a pair of cross heads or slides 38. The slides 38 are thus reciprocable toward and away from the supporting plate 25, and each carries on its upper side a block 39 fixed to the adjacent slide by fasteners 40. A generally vertically disposed cutting member or plate 41 is fixed to the laterally inward face of each block 39, as by fasteners 42a, so that each slide 38, and its secured block 39 and cutting member 41 are movable as a unit toward and away from the supporting plate 25. Further, the upper edge 42 of each upstanding cutting member 41, is movable with its respective assembly 38, 39 past the adjacent side edge 35 of the supporting plate 25 into position beneath the supporting plate with the upper edge in conforming engagement with the undersurface 27 of the supporting plate. Thus, the upper edge 42 of each cutting member 41 is serrated, as at 43, for conforming engagement in the serrations 36 of the nether supporting plate surface 27. It is now appreciated that the cutting members 41 will each coact with the supporting plate 25 to effect shearing and wiping of a material interposed therebetween upon inward movement of a cutting member. In addition, the cutting members 41 may be configured in the plan view as seen in Fig. 1 each similarly to the adjacent side edge 35 of the supporting plate 25 to thereby effect a substantially instantaneous shearing action. That is, each cutting member 41 is of a configuration similar to its adjacent side edge 35 of the supporting plate 25 so that all shearing coaction therebetween occurs simultaneously.

Mounted on the extreme lateral portions of the base 10 are a pair of air actuatable cylinder and piston assemblies 45 each having a rod 46 extending laterally inward and rigidly or pivotally connected to the adjacent block 39. Upon air actuation of the cylinder and piston assemblies 45, the slides 38 and their associated cutting members 41 are caused to move toward and away from the supporting plate 25 into and out of shearing coaction with the latter. A pair of air conduits 47 and 48 are respectively connected to the outer and inner ends of each cylinder assembly 45 and extends therefrom into air communication with a manually or automatically actuatable control valve 49.

In Fig. 2 it may be observed that each control valve 49 includes a cylinder 50 and an axially reciprocable rod 51 carrying a pair of spaced pistons 52 and 53 in the cylinder. Suitable resilient means, such as a spring 54 yieldably urges the pistons 52 and 53 in the direction of their reciprocation, while a manually or automatically actuatable lever 55 is operatively connected to the rod 51 to effect piston movement in the opposite direction of their reciprocation. At opposite end regions of the cylinder 50 are provided exhaust ports 56 and 57, respectively adjacent to the pistons 52 and 53, while an inlet conduit 58 is connected to a medial region of the cylinder 50 between the pistons 52 and 53. The conduit 47 is connected to the cylinder 50 between the exhaust port 56 and inlet conduit 58, while the conduit 48 is connected to the cylinder 50 between the exhaust port 57 and the inlet

conduit. Thus, in one extreme position of movement of the pistons 52 and 53, say the solid line position of Fig. 2, one exhaust port 57 is closed by its adjacent piston 53 and the adjacent conduit 48 is placed in communication with the inlet conduit 58, while the other exhaust port 56 is placed in communication with the conduit 47. As the conduit 48 is connected to the laterally inner end of its cylinder assembly 45, pressure is applied through the latter to effect withdrawal of the associated piston 46 and cutter member 41 away from the supporting plate 25. Conversely, in the opposite extreme position of movement of the piston rod 46 and cutter member 41 away from the supporting plate 25, the conduit 47 is connected to the laterally inner end of its cylinder assembly 45, pressure is applied through the conduit 47 to move the piston rod 46 and associated cutter 41 laterally inward to its limiting position of movement toward the supporting plate.

20 Mounted on the rear side of the block 22 is an upstanding support or standard 60, which is reinforced by a brace 61. On the forward side of the standard 60, adjacent to the upper end thereof, is mounted a vertically disposed cylinder 62 through which is vertically reciprocable a piston rod 63 carrying a piston 64 interiorly of the cylinder. A coil compression spring 65 may be circumposed about the piston rod 63 having its opposite ends in bearing engagement with the piston 64 and the upper end of the cylinder 62 to resiliently urge the piston rod vertically downward.

On the lower end of the piston rod 63, generally directly over the horizontal rearward portion 28 of the supporting plate 25, is a vertically disposed housing 67, which is rigidly carried by the piston rod. A slide member 68 is vertically slidable within the housing 67 having its lower end projecting through the bottom of the housing and retained in the housing by a pair of laterally outwardly projecting lugs 69. The lower end surface 70 of the slide member 68 is slightly convex for conforming engagement with a heel, as will appear presently. A coil compression spring 71, or other suitable resilient means, yieldably urges the slide member to its lowermost position relative to the housing 67.

The cylinder 62 and its piston 64 are operated by a 45 valve generally designated 74 including a cylinder 75 containing an axially slidable rod 76 which carries a pair of spaced pistons 77 and 78. The rod and piston assembly 76, 77 and 78 is resiliently urged to one extreme position of its movement by a spring 79, or other suitable 50 means, and a manually or foot actuatable or automatically actuatable lever 80 is operatively connected to the rod 76 for affecting shifting movement of the latter in the opposite direction of its movement. An air inlet conduit 81 is connected between the air inlet conduit 58 and an intermediate region of the cylinder 75, while an exhaust port 82 is provided in the cylinder at a location spaced from the conduit 81. At a location between the inlet conduit 81 and the exhaust port 82, a conduit 83 has one end connected to the cylinder 75 and has its other end connected 60 to the cylinder 62 below the piston 64. In the illustrated position of the valve 74, the piston 77 closes the exhaust port 82, and the inlet conduit 81 communicates through the cylinder 75 and conduit 83 with the cylinder 62 beneath the piston 64 to urge the latter to its uppermost 65 position, thus withdrawing the rod 63 and its yieldable clamping member 68 upward away from the supporting plate 25. However, upon actuation of the lever 80, the inlet conduit 81 may be closed by the piston 77 and the cylinder 62, through the conduit 83 and cylinder 75 may 70 exhaust through the port 82, thereby permitting downward movement of the piston 64 under the force exerted by spring 65, and consequent movement of the clamping member 68 toward the supporting plate 25.

In Fig. 6 is shown a heel, generally designated 90, in 75 an intermediate stage of manufacture. A heel body 91

may be of any desired construction, conventionally having a concave front surface or breast 92. A flexible covering or sheet 93 is adhesively secured to the heel body 91, being wrapped about the back and sides of the heel body in facing engagement therewith. The covering sheet 93 extends forward from the sides of the heel body beyond the breast 92, there defining forward extension or marginal portions 94 on opposite sides of the breast. Before applying a covering material to the breast 92 of the heel body 91, it is essential that the forward extensions or marginal portions 94 of the covering sheet 93 be reduced to a minimum size and pined or serrated so as to lie absolutely flat against the breast surface 92 without bunching or causing wrinkling on the sides.

By the method and apparatus of the present invention, it is only necessary to place the heel 90 on the supporting plate 25 with the outer surface 26 of the supporting plate in conforming supporting engagement with the breast surface 92 of the heel body, as best seen in Fig. 3. The marginal extensions 94 of the covering sheet 93 then extend closely along the respective side edges 35 of the supporting plate and beyond the undersurface 27 of the latter.

A firm but gentle clamping action (mechanical or hand) to secure the heel 90 in position on the supporting plate 25 may be achieved by actuation of the valve 74 to lower the rod 63 and clamping member 68, the latter firmly and yieldably engaging the back side of the heel above the generally horizontal portion 28 of the supporting plate to retain the heel in position on the plate.

The valves 49 may then be actuated to the dot-and-dash outline position shown in Fig. 2, which will effect inward movement of the cutting members 41 toward the supporting plate 25 into shearing coaction with the undersurface of the latter, as best seen in Fig. 5. The excess marginal portions are thereby removed, as at 95 to produce the heel 90a of Fig. 7. In such heel, the marginal portions 94a of the covering sheet 93a have been reduced to the proper size and formed with serrations, as at 96 along the arcuate region of the breast surface 92 to insure proper facing engagement of the marginal portions with the body breast surface.

While the device of the present invention has been illustrated and described as being manually operated, as in the feeding of a heel 90 into position on the supporting plate 25, and in operation of the foot valve 74 and hand valve 49, it is appreciated that such feeding and valve operation may be performed automatically, without human manipulation, if desired. The entire device can be operated with the clamping means as shown, or held by hand. It is desirable for a beginner operator to use the clamping means to learn locating of the heel on the supporting plate 25. After the operator becomes experienced, the clamping may be removed.

Of course, it is understood that the method and apparatus of the instant invention are capable of employment in conjunction with a wide variety of styles and sizes of heels, it being only necessary to remove and replace the supporting plate 25 and the cutting member 41 for use with a heel of different breast surface configuration if the work is not performed satisfactory with the dies described. There does not have to be perfect conformance as a finished covering goes over the heel breast.

In the embodiment of Fig. 8, the cross heads or slides 38 are mounted on the base member 10, each slide carrying a block 39, all in substantially the same manner as described in connection with the embodiment of Figs. 1-4. By way of difference, a support member 25a, corresponding to the supporting plate 25, is a solid piece detachably but fixedly secured in position, as to the mounting blocks 20 and 22, see Fig. 9. The upper surface 26a of the supporting member 25a is configured for conforming supporting engagement with the heel body 91, the heel body covering sheet 93 having its marginal extensions 94 ex-

tending closely along the respective side surfaces 93a of the supporting member.

Further by way of distinction, each of the blocks 39 carries a cutting member 41a, which cutting members differ from the hereinbefore described cutting members 41 by the provision of an inwardly extending knife edge or die cutting blade 44a along its upper edge configure for conforming die cutting engagement with the adjacent side surface 93a of the supporting member 25a. Thus, upon inward movement of each assembly 38, 39 and 41a, its associated cutting edge 44a moves into die cutting coaction with the adjacent supporting member surface 93a for severing a portion of the adjacent covering extension 94.

While the cutting members 41a of Fig. 8 are illustrated at different distances from the supporting member 25a, one engaging the latter and the other spaced from the supporting member, it is understood that the cutting members preferably move symmetrically for simultaneous cutting engagement with the sheet material covering 93, but are shown in the different positions for purposes of clarity of illustration.

In addition to the marginal extensions 94 of the heel body covering sheet 93, the covering sheet extends longitudinally beyond the lower heel end, as at 100, see Figs. 9 and 11, along the back and sides of the heel body, being generally of U-shaped configuration in transverse cross section.

A spring biased backing member 101 is mounted on the rearward, generally horizontal portion of the upper supporting member surface 26a, being carried on the forward end of a forwardly and rearwardly extending, generally horizontally disposed rod 102 longitudinally slidable in upstanding bearings 103 and 104. The backing member 101 is of a configuration adapted to conformably engage beneath the lower end extension or marginal portion 100 of the cover sheet 93, and in flat facing engagement with the upper supporting member surface 26a, so as to be non-rotatable relative to the supporting member. An upstanding arm 105 is carried by the rod 102, extending upward and forward therefrom, and fixed thereto for forward and rearward shifting movement with the back member 101. Suitable resilient means may be employed to urge the unitary arm 105, rod 102 and backing member 101 forward, to a limiting position, say by engagement of the arm with the bearing 103. For this purpose, coil compression spring, as at 106 may be circumscribed about the rod 102 between the arm 105 and bearing member 104, and in bearing engagement with the arm and bearing member to yieldably urge the unitary assembly forward.

Extending vertically through the upper end of the arm 105, directly over the backing member 101, is a rod 110, which has an enlarged head on its upper end above the upper arm end, and a cutting member 112 on its lower end, below the upper arm end. The rod 110, together with its head 111 and cutting member 112 are vertically slidably mounted in the upper end of the arm 105; and, a coil compression spring 113 is circumscribed about the rod having its opposite ends in engagement with the head 111 and upper mounting portion of the arm 105 resiliently urge the rod vertically upward. The cutting member 112, as best seen in Figs. 9 and 10, is of a generally downwardly opening and slightly outwardly flaring U-shaped configuration, and is provided on its inner side with a knife edge or die cutting blade 114. The configuration and dimensions of the cutting member 112 and its knife edge 114 are such as to engage with the downwardly extending heel body covering sheet portion 100 to sever the latter as desired upon downward movement of the cutting member 112. That is, the cutting member 112 by its knife edge 114 effects die cutting engagement through the cover sheet portion 100 to the backing member 101. While the knife edge 114 may be of any desired configuration, one such configura-

tion is illustrated in the drawings, such as to define a notch 115 in the remaining cover sheet portion to facilitate inward folding thereof. Downward movement of the unitary assembly 110, 111 and 112 may be effected by downward movement of the hammer or striker 116 against the head 111, and the assembly will return upward under the force of spring 113.

From the foregoing it is seen that the method and apparatus of the present invention enable an operator to more quickly, efficiently, and perfectly perform the heel cover severing operation, and that the instant method and apparatus fully accomplish their intended objects and are well adapted to meet practical conditions of commercial use.

There have been described two separate facets of cutting, namely breast lift cutting and top lift cutting. These cutting operations can be performed at the same time. Knife die 114 can be a male die instead of a knife die and be utilized on breast severing male and female dies set-up. The breast cutting means can likewise be a knife die or male and female set-up. If desired, continuations of such die arrangements may be utilized.

Although the present invention has been described in some detail by way of illustration and example for purposes of clarity of understanding, it is understood that certain changes and modifications may be made within the spirit of the invention and scope of the appended claims.

What is claimed is:

1. Apparatus for severing a covering sheet applied to a heel body, said apparatus comprising a supporting plate having one face engageable with the breast of a heel body with the covering sheet extending on opposite sides of the supporting plate beyond the other face thereof, and cutter members movable past said opposite sides of said supporting plate in shearing coaction with said other face thereof to sever the extending portions of said covering sheet.

2. Apparatus according to claim 1, in combination with clamping means movable toward and away from said one face of said supporting plate for releasably clamping a heel in position on said plate.

3. Apparatus according to claim 1, said other face of said supporting plate being serrated, and said cutter members being serrated for conforming engagement with said other face of said supporting plate to provide serrations along the severed edges of said covering sheet.

4. Apparatus for severing a covering sheet applied to a heel body, said apparatus comprising a fixed supporting plate configured to have one face conformably engageable with the breast of a heel body with the covering sheet disposed on opposite sides of the supporting plate extending beyond the other face thereof, and a pair of cutter members mounted on opposite sides of said supporting plate for reciprocation past the respective adjacent side edge of said supporting plate into and out of shearing coaction with said other face of said supporting plate to sever the extending portions of said covering sheet.

5. Apparatus according to claim 4, said supporting plate having said one face laterally coextensive with the breast of the heel body for extension of said covering sheet closely adjacent to the side edges of said supporting plate.

6. Apparatus according to claim 4, in combination with a clamping member selectively movable toward and away from said one face of said supporting plate for clamping and releasing a heel from said position.

7. Apparatus according to claim 6, in combination with independently manually actuatable means for effecting reciprocation of each of said cover members, an additional foot actuatable means for selectively effecting movement of said clamping member.

8. Apparatus for severing a cover sheet applied to the heel body, said apparatus comprising a generally hori-

zontal base, a supporting plate fixedly mounted on said base in spaced relation thereabove having a convex surface facing generally upwardly and forwardly and having concave surface facing generally downwardly and rearwardly, a pair of slides mounted on said base on opposite sides of said supporting plate and each movable toward and away from the latter, a cutting member carried by each of said slides for movement therewith into and out of position beneath said supporting plate past the adjacent side edge of said supporting plate in shearing coaction with said other surface thereof, means for selectively effecting movement of said cutter members into and out of said shearing coaction with said supporting plates, and a clamping member arranged over said supporting plate and mounted on said base for up and down movement toward and away from said supporting plate.

9. Apparatus according to claim 8, said means for effecting cutter member movement being independently manually actuatable, and independently foot actuatable means for effecting movement of said clamping member.

10. Apparatus for severing a covering sheet applied to a heel body, said apparatus comprising a fixed supporting member configured to have one face conformably engageable with the breast of a heel body with the covering sheet disposed on opposite sides of the supporting member, and a pair of cutting members mounted on opposite sides of said supporting member for reciprocation into and out of cutting coaction with said supporting member to sever the extending marginal sheet material portions.

11. Apparatus according to claim 10, said cutting members comprising die cutters movable into and out of die cutting engagement with respective sides of said supporting member.

12. Apparatus for severing a covering sheet applied to a heel body, said apparatus comprising a fixed supporting member configured to have one face conformably engageable with the breast of a heel body with the covering sheet disposed on opposite sides of the supporting plate and extending beyond the end of the lower heel end, a backing member removably seated on said one face of said supporting member engageable beneath the downwardly extending covering sheet portion of a heel positioned on said supporting member, and a cutting member mounted for movement toward and away from said one face of said supporting member and said backing member for movement into and out of cutting engagement with the extending portion of said covering sheet engaged over said backing member.

13. Apparatus for trimming heel covers comprising a base, a plurality of die members comprising a central die member stationarily mounted on said base and having a heel-engaging face substantially conforming to the breast of a heel and two side die members mounted on said base at opposite sides of said central die member for movement toward and away from said central die member between a cutting position and a retracted position, said die members having cooperating cutting edges

to cut both sides of said heel cover between said central die member and said side die members along a line spaced forwardly of the breast of a heel positioned on said heel-engaging face, and power means for moving said side die members toward and away from said central die member between said retracted position and said cutting position.

14. Apparatus according to the base claim 14, in which said cutting edges include zig-zag portions to cut said heel cover along zig-zag lines.

15. Apparatus according to the base claim 14, in which said power means comprise a pneumatic power unit for each of said side die members.
